J. H. COX.
RAILWAY WHEEL REPLACING AND DERAILING DEVICE.
APPLICATION FILED AUG. 5, 1920.
1,372,646. Patented Mar. 22, 1921.

UNITED STATES PATENT OFFICE.

JOHN H. COX, OF HOT SPRINGS, ARKANSAS.

RAILWAY WHEEL REPLACING AND DERAILING DEVICE.

1,372,646.

Specification of Letters Patent. Patented Mar. 22, 1921.

Application filed August 5, 1920. Serial No. 401,417.

To all whom it may concern: Be it known that I, JOHN H. COX, a citizen of the United States, residing at Hot Springs, in the county of Garland and State of Arkansas, have invented certain new and useful Improvements in Railway Wheel Replacing and Derailing Devices; and I do hereby declare the following to be a full, clear, and exact description of the invention, such as will enable others skilled in the art to which it appertains to make and use the same, reference being had to the accompanying drawings, and to the letters and figures of reference marked thereon, which form a part of this specification.

One object of my invention is to provide a novel construction of car replacing device which, by its peculiar construction, may be made very light in weight without sacrificing any of its efficiency.

Another object is to provide a device of the character described provided with a portion peculiarly constructed to engage a railroad rail in a manner to prevent sidewise movement of the device.

Another object is to provide a car replacing device comprising a pair of plates, one of the plates being of somewhat different construction from the other and the two plates being adapted for use one on the left hand railroad rail and the other on the right hand rail; and the plate adapted for use on the left hand rail being also susceptible for use on the right hand rail as a derailing device.

The accompanying drawing clearly discloses the preferred form of my device, like reference characters designating corresponding parts throughout the several views.

Briefly described:

Figure 1 is a collective view in top plan of the pair of car replacing plates shown in operative position upon the right and left hand rails of a railroad track;

Fig. 2 is a view in vertical transverse section along the line 2, 2 of Fig. 1, looking in the direction of the arrows thereon;

Fig. 3 is a collective view of the car replacing plates detached from the rails, and

Fig. 4 is a view in top plan of one of the plates used as a derailer.

Referring now in detail to the drawing:

My car replacing device comprises, as indicated above, two car replacing plates des-

ignated in the drawings by the reference numerals 1 and 2.

Referring to Fig. 1, the railroad rail 3 is supposed to be the right hand rail and the rail 4 the left hand rail, the plate 1 being adapted for use on the rail 3 and the plate 2 on the rail 4.

Taking up first in detail the construction of the plate 1, it will be seen that this plate is roughly triangular in shape and is of gradually decreasing width from one end thereof to the other. The base of the triangular shaped plate is adapted to contact with the road bed, as shown in Fig. 2, and is consequently in the plane of the base flanges 4' of the rail 3, said base being the greatest width of the plate. Thence the plate curves upward, as shown at 5, so that all but the marginal edge of the base of the plate is elevated above the road bed. The highest point of the plate 1 is, as shown in Fig. 1, somewhat below the top flange, or tread portion of the rail 3. One of the longitudinal edges of the plate 1 is upwardly inclined, as shown at 6, said upward inclined portion, or flange 6, being inclined with respect to the remaining longitudinal edge 7 of the plate. Said upward inclined portion 6 constitutes a guide flange to direct the car wheel toward the rail 3 when the car wheel moves up upon the plate 1 along the curved portion 5 thereof. The flange 6, at the end thereof, adjacent the narrowest portion of the plate, is disposed to one side of the rail 3 when the plate is in operative position upon the rail.

The longitudinal edge 7 of the plate is provided with an inverted U-shaped hook portion 8, adapted to hook over the rail 3, as shown in Figs. 1 and 2, thus functioning as a clamp, or clutch, to maintain the plate

sidewise displacement in use. One of both of the depending flanges of the said U-shaped portion 8 may be perforated, as shown at 9, for the purpose of lightness in weight. The flange 6 is doubled upon itself for a portion of its length, as shown at 9', and terminates in a depending flange 10, adapted to bear squarely against the road bed and functioning as a brace. This depending portion 10 is shown in the dotted lines in Fig. 3 and in section in Fig. 2, and is provided with a longitudinally extending series of perforations 11 for the purpose of lightening the weight of the structure.

Referring now in detail to the form of plate 2 used in connection with the left hand rail 4, it will be seen that this plate somewhat resembles the plate 1, but differs therefrom in the respects now to be described.

The plate 2 rises above the rail 4 so as to extend thereover and bear thereagainst, and is, therefore, somewhat higher than the plate 1. One side of the plate 2 is provided with a depending flange 12 adapted to bear against one side of the rail 4, as shown in Fig. 2, and is perforated as shown at 13 for the sake of lightness. The plate 2 is also provided with a second depending flange 14, parallel with the flange 12 and adapted to bear against the other side of the rail 4. The other marginal side of the plate 2 is provided with the upward inclined flange 15, similar to the flange 6 of the plate 1, and this flange 15 terminates at one end thereof at a point above and in the same vertical plane as the rail 4. This flange 15, like the flange 6, is doubled upon itself, as shown at 16 and terminates in a depending flange 17, similar to the flange 10 of the plate 1, and is adapted to bear against the road bed and to brace the plate in the manner of the flange 10 of plate 1.

In operation, the wheels of the derailed railroad car will strike against the base por-

tion of the plates and will ride up thereon, the car wheels being guided by contact with the inclined flanges 6 and 15 toward the rails 3 and 4, so that, as the said car wheels leave the flanges 6 and 15 at the high ends thereof they will be in a position to roll upon the rails 3 and 4, thus replacing the car on said track rails.

The plate 2 may be used, if desired, as a derailer and for this purpose is placed on the right hand track 3, as shown in Fig. 4.

What I claim to be new is:

1. The combination with a rail embodying a tread, a supporting web, and a base under the web wider than the tread, of a unitary 45 pressed sheet metal replacer having an inclined surface and a rib converging with the rail and downwardly turned integral flanges spaced to embrace the tread and to bear upon the base.

2. A replacer composed of sheet material having means for engaging a rail and having an upwardly turned marginal flange converging with the rail, said flange being composed of the sheet material bent upon itself 55 with the edge extending downwardly as a supporting flange.

In testimony whereof I hereunto affix my signature.

JOHN H. COX.
